CONTAINER FOR A ROOM-DEODORANT
DIFFUSER OR THE LIKE

Stanley R. Mallory, Jr., 15306 Hastings Drive, Dolton, Ill.

Filed May 20, 1960, Ser. No. 60,667

Term of patent 3½ years

(Cl. D58—9)

Fig. 1.

The dominant features of my design reside in the portion shown in full lines.

I claim:

The ornamental design for a container for a roomdeodorant diffuser or the like, substantially as shown and described.
